UNITED STATES PATENT OFFICE

HERMAN SOBEL, OF NEW YORK, N. Y.

DESIGN FOR A SIGN FRAME

Application filed March 18, 1933. Serial No. 47,506. Term of patent 3½ years.

To all whom it may concern:

Be it known that I, HERMAN SOBEL, a citizen of the United States, residing at New York city, in the county of New York and State of New York, have invented a new, original, and ornamental Design for Sign Frames, of which the following is a specifica- tion, reference being had to the accompany- ing drawing, forming part thereof.

Fig. 1 is a face view of a sign frame showing my new design.

Fig. 2 is an end view of the same.

I claim:

The ornamental design for a sign frame as shown.

In testimony whereof I have affixed my signature.

HERMAN SOBEL.
